John H. Horman, Tuckahoe, N. Y., assignor, by
mesne assignments, to Allied Control Company,
Inc., New York, N. Y., a corporation of New
York

Application May 31, 1943, Serial No. 489,168

9 Claims. (Cl. 200—12)

1

This invention relates to switches.

An object of this invention is a rotary switch which is automatically retained in closed position upon actuation to such position and may be restored to open position by remote control.

Another object of the invention is the provision in a rotary switch of means biasing it to open position and electromagnetic means effective upon the closing of the switch to overcome the bias as long as said electromagnetic means remains energized.

In one embodiment of the invention, the switch includes a shaft rotatable between a first and a second position with movable contacts carried by the shaft. Stationary contacts are provided in such arrangement that with the shaft in its first position the movable and stationary contacts are disengaged but with the shaft in its second position the movable and stationary contacts are engaged. The shaft is biased toward its first position and there is provided electromagnetic means co-operating with means carried by the shaft to retain the shaft in its second position when the electromagnet is energized. Interruption of current flow in the energizing circuit automatically renders ineffective the retaining means so that the shaft returns to its first position under the influence of its bias.

Other objects, novel features and advantages of this invention will become apparent from the following specification and accompanying drawings, wherein:

Fig. 1 is a plan view of a switch embodying the invention;

Fig. 2 is a side elevation of Fig. 1;

Fig. 3 is a section on the line 3—3 of Fig. 2;

Fig. 4 is a section on the line 4—4 of Fig. 2;

Fig. 5 is a section on the line 5—5 of Fig. 2;

Fig. 6 is a section on the line 6—6 of Fig. 2;

Fig. 7 is a circuit diagram;

Fig. 8 is a plan view of a modification;

Fig. 9 is a side elevation of Fig. 8;

Fig. 10 is a section on the line 10—10 of Fig. 9;

Fig. 11 is a section on the line 11—11 of Fig. 9;

Fig. 12 is a section on the line 12—12 of Fig. 9;

Fig. 13 is a section on the line 13—13 of Fig. 9; and

Fig. 14 is a circuit diagram.

A pair of rod-like members 10 support a plurality of spaced metal plates 11, 12, 13, 14 and 14a and also a plurality of disks 15 of insulating material. The plates 11 and 12 are of general elliptical configuration and in them is journalled a shaft 16 which extends through

2

notches in the metal plates 13, 14 and 14a and through apertures in the disks 15.

Each of the plates 11 and 12 has fixed to it one end of a wire spring 17, the other end of which extends through a notch 18 in the plate toward the remaining plate, the two notches being slightly offset from each other. The projecting ends 19 of the springs 17 are biased toward opposite ends of the notches 18 and tend to engage such ends in spaced relation to each other. The shaft 16 carries an arm 20 which extends between the projections 19. Rotation of the shaft 16 in either direction is opposed by one of the springs 17 and the extent of permissible rotation of the shaft 16 in either direction is limited by the length of the notches 18, the ends of which are engageable by the projections 19 which act as stops for limiting the extent of movement of the arm 20 as shown in dotted lines in Fig. 5. The springs bias the shaft 16 to a position of rest in which the arm 20 is engaged by both projections 19.

The plates 14 and 14a support a U-shaped member 21 of magnetic material in which is arranged the coil 22 and core 23 of an electromagnet. One leg of the U-member 21 is provided with ears 21a in which is supported a pin 24 pivotally supporting an armature 25 co-operating with the coil 22. The armature has a right-angle extension 26 having a central rib 26a formed with sloping shoulders 27. A spring 28 biases the armature toward the core 23.

The shaft 16 extends through both legs of an L-shaped member 29 having non-round apertures and the shaft being of the same configuration so that the L-shaped member is mounted on the shaft for rotation therewith. A set screw 30 is provided to maintain the member 29 in any desired position axially of the shaft. The long leg of the member 29 carries a fan-shaped plate 31 which is slit as indicated at 31a and offset to form tabs 32 projecting slightly from the plate toward the armature extension 26. The arrangement of the member 29 on the shaft 16 is such that with the shaft 16 in its rest position the tabs 32 are symmetrically arranged with respect to the center line of the extension 26 and the rib 26a projects into the path traversed by either tab 32 upon rotation of the shaft 16 in either direction from its position of rest. The plate 13 supports a bar 33 of insulating material on which are mounted terminals 34 and 35 to which are connected lead wires 36 respectively for the coil 22.

When in use, the above-described switch is incorporated in the circuit shown in Fig. 7. A conductor 37 leads from the terminal 34 through a source of electrical energy 38 to a switch 39 from which a conductor 40 leads to the terminal 35. Whenever the switch 39 is closed, there is current flow through the coil 22 to energize the electromagnet and attract the armature 25 toward the coil 22.

Rotation of the shaft 16 in either direction causes movement of the plate 31 to swing the armature clockwise against the action of the spring 28 and the pull of the electromagnet, if energized, until a tab 32 clears the rib 26a and opposes a shoulder 27 by reason of counter-clockwise rotation of the armature under the influence of the spring 28 and the pull of the electromagnet, if energized. With the electromagnet energized, the armature is held in such position by electromagnetic force sufficient to retain the shaft in its rotated position against the bias of the spring 17. If for any reason the coil circuit is broken, the electromagnet becomes de-energized and the armature is biased in the aforementioned position solely by the spring 28 which is of insufficient strength to prevent the return movement of the shaft 16 to its position of rest under the influence of the spring 17.

The shoulders 27 are slightly sloping so that they, together with the tabs 32, constitute an impositive lock which is effective to overcome the bias exerted on the shaft 16 by the spring 17 when the electromagnet is energized. The shaft, however, is not positively locked in its actuated position but may be returned to its rest position by sufficient force applied to the shaft 16. The pull of the electromagnet is less than sufficient to retain the shaft 16 in either of its actuated positions against the force which may be manually applied by the average person to the shaft 16. The shaft, therefore, may be returned to its rest position by manual operation as well as by de-energization of the magnet through opening of the switch 40. The switch 39 may be located at some distance from the device which is the subject of this application, thereby permitting remote control return of the shaft 16 to its rest position. The shaft 16, however, can be rotated only manually out of its rest position. To facilitate such manual rotation of the shaft, the electromagnet may be de-energized either by opening the switch 39 or a similar switch conveniently placed but such switches must be closed with the shaft 16 retained in actuated position or else the shaft will be returned to its rest position by a spring 17 immediately upon release of the force exerted to it to put it in its actuated position.

In the embodiment illustrated in Figs. 8 to 14, rods 10a support plates 11a and 12a and a metal plate 41. The plates 11a and 12a carry springs 17a having portions 19a extending through notches 18a in the plates. The shaft 16a carries an arm 20a extending between the projections 19a. The springs 17a bias the shaft 16a to a position of rest in which the arm 20a engages both projections 19a.

The plate 41 supports a U-shaped member 21a of magnetic metal in which is arranged a coil 22a having an iron core 23a. The member 21a is attached to the plate 41 in such manner that the shaft 16a passes through the bight of said member and through the coil core 23a. An armature 25a is supported by the shaft 16a for rotation therewith by means of an L-shaped

member 29a through both legs of which the shaft 16a passes. The armature touches the ends of the U-shaped member and core 23a but is rotatable with the shaft relative thereto. Preferably, one leg of the member 21a is shaped at its outer end to conform to the coil 22a.

A pair of resilient conductor plates or arms 42 and 43 are supported from one leg of the U-shaped member 21a by a series of insulating pads 44 through which extend bolts 44a threaded into the leg. The plates are insulated from each other and from the member 21. The arm 42 has a terminal 42a while the arm 43 is provided with a terminal 34a and the coil 22a is connected to a terminal 35a and the terminal 42a through conductors 36a. The arm 42 is shorter than the arm 43 and has a right-angle flange 45 extending toward the arm 43 while the free end of the arm 43 overlies an edge of the armature 25a.

A plate 46 is insulatingly supported by the member 21a between the arm 43 and an edge of the armature 25a and is held in place by bolts 47. This plate has an aperture in which is arranged a ball 48 for engagement by the adjacent edge of the armature 25a, such edge being provided with three recesses 49. The plate 43 engages the ball 48 and serves to bias it into contact with the edge of the armature 25a. When the ball is received in any one of the notches 49, the arm 43 engages the flange 46 but when the ball is engaged by a part of the armature edge between notches, the arm 43 is disengaged from the flange 46. The arrangement of the notches is such that the ball is received in the center notch 49 when the shaft 16a is in its rest position and in one of the other notches when the shaft is rotated in either direction the extent of its permissible movement.

In the operation of this switch, the terminal 34a is connected by a conductor 37a through a source 38a of electrical energy to a switch 39a from which a conductor 40a leads to the terminal 35a. With the switch 39a closed, rotation of the shaft 16a in either direction first actuates the ball 48 to disengage the arm 43 from the arm 42 to open circuit the 22a. This circuit remains open until the shaft reaches approximately the limit of its movement in either direction as shown in dotted lines in Figs. 1, 2 and 3 whereupon the ball is received in one of the remaining notches thereby closing the coil circuit and establishing magnetic flux through the member 21a and armature 25a thereby holding the shaft 16a in actuated position against the bias of the spring 17a. The shaft 16a may be returned to its rest position by opening the switch 40a whereupon the magnetic pull on the armature 25a will be relieved and a spring 17 will be effective to return the shaft 16a to its rest position. Also, the shaft may be returned to its rest position by the manual application of sufficient force to the shaft to overcome the magnetic pull on the armature. A very slight rotation of the armature 25a is effective to move the ball 48 sufficiently to disengage the arm 43 from the arm 42 thereupon opening the coil circuit and interrupting the magnetic pull. The shaft 16a may then be easily returned to its position of rest whereupon the ball 48 enters the middle notch and re-establishes the coil circuit.

Each disk 15 supports one or more sets of three contacts 51 and 52 which are radially arranged and are adapted to be connected to conductors

leading to electrical apparatus to be controlled. The shaft 16 is provided with a plurality of insulating hubs 53, each of which supports three contact members 54 having a radially extending portion 55 of slightly greater width than the gap between the adjacent disk-carried contacts. The arrangement of the contacts 54 with respect to the shaft 16 is such that when the shaft is in its rest position, each portion 55 engages merely a contact 51. Upon rotation of the shaft 16 from either rest position, the full extent of its permissible movement, the portion 55 is caused to bridge either the contact 59 and contact 51 or contact 51 and contact 52. Thus, with the shaft 16 in its rest position, all the controlled circuits are open but with the shaft 16 in either of its extreme positions, one half of the controlled circuits are closed with the remaining half open.

I claim:

1. In a switch, a shaft rotatable between a first and a second position, movable contacts carried by and fixed to said shaft, stationary contacts, said movable and stationary contacts being in one circuit relation with the shaft in its first position and in another circuit relation with the shaft in its second position, means biasing said shaft toward its first position, a stationary electromagnet having an armature provided with an extension, and interengageable means on said extension and said shaft for retaining said shaft in its second position when said electromagnet is energized.

2. In a switch, a shaft rotatable between a first and a second position, movable contacts carried by and fixed to said shaft, stationary contacts, said movable and stationary contacts being in one circuit relation with the shaft in its first position and in another circuit relation with the shaft in its second position, means biasing said shaft toward its first position, a stationary electromagnet having an armature provided with an extension, and an arm carried by and fixed to said shaft and engageable by said extension when the electromagnet is energized to retain said shaft in its second position.

3. In a switch, a shaft rotatable between a first and a second position, movable contacts carried by and fixed to said shaft, stationary contacts, said movable and stationary contacts being in one circuit relation with the shaft in its first position and in another circuit relation with the shaft in its second position, means biasing said shaft toward its first position, a stationary electromagnet having an armature provided with an extension member, an arm member carried by and fixed to said shaft, said two members having surfaces inter-engageable when said electromagnet is energized to retain said shaft in its second position, at least one of said surfaces being oblique to its direction of movement to produce a cam effect by said arm member on said extension member upon rotation of said shaft.

4. In a switch, a shaft rotatable between a first and a second position, movable contacts carried by said shaft, stationary contacts, said movable and stationary contacts being in one circuit relation with the shaft in its first position and in another circuit relation with the shaft in its second position, means biasing said shaft toward its first position, an electromagnet coaxial with said shaft and having an armature rotatable therewith, a switch in series with the coil of said electromagnet and biased to closed position, and

means for opening said switch upon partial rotation of its shaft from its first to its second position and permitting said switch to close upon arrival of the shaft in its second position.

5. In a switch, a shaft rotatable between a first and a second position, movable contacts carried by said shaft, stationary contacts, said movable and stationary contacts being in one circuit relation with the shaft in its first position and in another circuit relation with the shaft in its second position, means biasing said shaft toward its first position, an electromagnet coaxial with said shaft and having an armature rotatable therewith, a switch in series with the coil of said electromagnet and biased to closed position, and means including said armature for opening said switch upon partial rotation of its shaft from its first to its second position and permitting said switch to close upon arrival of the shaft in its second position.

6. In a switch, a shaft rotatable between a first and a second position, movable contacts carried by said shaft, stationary contacts, said movable and stationary contacts being in one circuit relation with the shaft in its first position and in another circuit relation with the shaft in its second position, means biasing said shaft toward its first position, an electromagnet coaxial with said shaft and having an armature rotatable with said shaft and a pair of contacts biased into engagement, and means for separating said contacts upon partial rotation of said shaft from its first to its second position and permitting re-engagement of said contacts upon arrival of the shaft in its second position, said pair of contacts being in series with the coil of said electromagnet.

7. In a switch, a shaft rotatable between a first and a second position, movable contacts carried by said shaft, stationary contacts, said movable and stationary contacts being in one circuit relation with the shaft in its first position and in another circuit relation with the shaft in its second position, means biasing said shaft toward its first position, an electromagnet coaxial with said shaft and having an armature rotatable with said shaft, a pair of contacts biased into engagement, and means including said armature for separating said contacts upon partial rotation of said shaft from its first to its second position and permitting re-engagement of said contacts upon arrival of the shaft in its second position.

8. In a switch, a shaft rotatable between a first and a second position, movable contacts carried by said shaft, stationary contacts, said movable and stationary contacts being in one circuit relation with the shaft in its first position and in another circuit relation with the shaft in its second position, means biasing said shaft toward its first position, an electromagnet coaxial with said shaft and having an armature rotatable with said shaft, a pair of contacts biased into engagement, and means effective with said shaft arranged between its first and second positions to separate said contacts while permitting engagement of said contacts when the shaft is in either its first or its second position.

9. In a switch, a shaft rotatable between a first and a second position, movable contacts carried by said shaft, stationary contacts, said movable and stationary contacts being in one circuit relation with the shaft in its first position and in another circuit relation with the shaft in its second position, means biasing said shaft toward its first position, an electromagnet coaxial with

said shaft and having an armature attached to said shaft, a pair of contacts in series with the coil of said electromagnet and biased into engagement, and means including said armature for supporting said contacts with the shaft arranged between its first and its second position while permitting engagement of said contacts when the shaft is in either its first or its second position.
